C. F. WICHMANN

FERRULE CONTRACTING MACHINE

Filed Aug. 3, 1922

INVENTOR :

Carl Frederick WICHMANN
By Attorneys,
Fraser, Funk & Myers.

UNITED STATES PATENT OFFICE.

CARL FREDERICK WICHMANN, OF BROOKLYN, NEW YORK, ASSIGNOR TO A. SCHRADE'S SON, INCORPORATED, OF BROOKLYN, NEW YORK, A CORPORATION OF NEW YORK.

FERRULE-CONTRACTING MACHINE.

Application filed August 3, 1922. Serial No. 579,510.

To all whom it may concern:

Be it known that I, CARL FREDERICK WICHMANN, a citizen of the United States of America, residing in borough of Brooklyn, county of Kings, city and State of New York, have invented certain new and useful Improvements in Ferrule-Contracting Machines, of which the following is a specification.

10 This invention relates to ferrule contracting machines, and aims to provide certain improvements therein.

15 The invention is particularly directed to that type of machine in which by a movement of the handle a plurality of jaws are brought forward to their inner or contracting position. The jaws may be restored to their outer or ferrule-receiving position by a reverse movement of the handle, or as in 20 certain forms of such machines a complete movement of the handle from side to side may actuate the jaws inwardly, and then outwardly.

25 The invention is applicable to such type of machine, and provides a device having a minimum number of parts, which is strong and durable, easily constructed, and cheap to manufacture.

30 In the drawings, wherein I have shown the preferred form of the invention,

Figure 1 is a side view, partly broken away.

Fig. 2 is a diametrical section on the line 2—2 in Fig. 1.

35 Fig. 3 is a diametrical section on the line 3—3 in Fig. 1.

Fig. 4 is a diametrical section on the line 4—4 in Fig. 1.

40 Referring to the drawings, I have shown the machine as comprising a side plate A which may be provided with means for being fastened to either a horizontal or vertical support, it being shown as having a foot B to adapt it for resting upon a table.

45 The side plate A is constructed with a plurality of lugs C C, the outer sides of which are curved at D to form a bearing for the movable member E. Preferably the lugs C are cast as a part of the side plate A, so that 50 their outer peripheries may be machined on a lathe in one operation. Each of the lugs is formed with straight sides F, the adjacent sides of each two lugs forming a rectilinear guide for one of the dies G. There are pref-

erably four of such dies, and their inner and 55 working faces are suitably configured in accordance with the work in hand. The dies illustrated have faces which when contracted form a circle, thus adapting the machine for uniform contraction of the ferrule. The 60 faces F of the lugs are so constructed that they can be machined diametrically completely across, thus facing either two or four surfaces simultaneously.

The movable member E is adapted to be 65 rotated in the present instance through an arc of about 45°, and during this movement is adapted to move the dies from a full open position to a full closed position, and then again to a full open position. In this adaptation of the invention the device is open at 70 the two extremes of its movement, and closed in its middle position, so that one stroke of the machine suffices to contract the ferrule, and reset it for the next operation. 75

The dies are moved by such rotative movement by means of links H H, each of which comprises a two-headed member, the heads being circular or substantially cylindrical in form, and the connecting part being of such 80 width so that the member when viewed from its end resembles a dumb-bell in shape, the inner head working in a circular recess I in one of the dies and the outer head working in a circular recess J formed in the rotative member. Preferably the links are of the same thickness as the dies. The circular recesses are cheaply formed by the use of a 85 drill press.

Another feature of the invention is the 90 ease with which the dies may be assembled and dis-assembled. The rotative member E is best provided with a flange E', which bears against the outer face of the lugs C, and which is best formed with a tapered face E'. The retaining ring K is provided, which best has a tapered periphery K', to correspond with the taper E' on the member E, and the retaining ring is best held in place by means of catch rods L, each of which has a head L' which passes through an elongated opening K' in the retaining ring, and which may be turned across the opening, as illustrated in Fig. 1 to hold the retaining ring in place. The catch rods 95 L preferably pass through to the opposite side of the side plate A, and are best provided with a flat head M, by means of 100 105

which they may be turned. A spring N normally holds the plates in place, and thereby secures all of the parts in operative position.

- 5 In assembling, the plate A is preferably laid on its side, with the rotative member in position, the dies adjusted in position, and the links applied, whereupon the rods L are pushed forward from the rear and 10 slipped through the openings K, whereupon they are turned. The device is then ready for use. To assist in removing the maintaining ring, recesses O may be supplied in the face of the rotative member E.
- 15 To insure the proper positioning of the ring, pins P may be provided on opposite lugs which enter holes P' in the ring.

I have shown the device as adapted for hand operation, in which case a suitable 20 handle Q will be provided.

While I have shown and described one form of the invention, it will be understood that I do not wish to be limited thereto, since various changes may be made there- 25 in without departing from the spirit of the invention.

What I claim is:—

1. A contracting machine comprising a side plate having lugs the exterior surfaces 30 of which are circular in form, said lugs having their opposing faces constructed to form slideways, jaws in said slideways, a circular operating member fitting said exterior circular surfaces of the lugs and carrying members adapted to operate said jaws, said members being links formed with enlarged substantially cylindrical heads fitting into circular recesses in said operating member and jaws.
- 40 2. A contracting machine comprising a side plate having lugs the exterior surfaces

of which are circular in form, said lugs having their opposing faces constructed to form slideways, jaws in said slideways, a circular operating member fitting said exterior circular surfaces of the lugs and carrying members adapted to operate said jaws, said operating member and jaws having circular recesses open toward each other and being laterally open, and double-headed links passing laterally into said recesses. 45

3. A contracting machine comprising a side plate having lugs the exterior surfaces of which are circular in form, said lugs having their opposing faces constructed to form 50 slideways, jaws in said slideways, a circular operating member fitting said exterior circular surfaces of the lugs and carrying members adapted to operate said jaws, and means for holding said operating member 55 in position, said means comprising spring bolts having heads adapted to be passed through elongated openings in said holding means and to be turned to secure the latter in place. 60

4. A contracting machine, comprising a plate having lugs, the exterior surfaces of which are circular, and a rotative member having a bearing on said circular faces, said lugs having their opposing surfaces constructed to form slideways, radially moving dies in said slideways, and links connected with said rotative member and said dies, said dies and links constructed to be separated laterally, and a retaining ring for 75 holding the parts together, said retaining ring being held in position by spring rods having heads engaging the outer surface of said ring. 70

In witness whereof, I have hereunto signed my name.

CARL FREDERICK WICHMANN.
